UTENSIL WASHING MACHINE

Alfred H. Haberstump, Detroit, Mich.

Application May 2, 1938, Serial No. 205,433

11 Claims. (CL 141—9)

This invention relates to washing machines.

One of the objects of the invention is the provision of a washing machine which is compact in its arrangement, simple in construction, is efficient in operation, and is capable of operating continuously, thereby making it especially suitable for household uses and is readily adaptable to industrial or commercial uses.

Another object of the invention is the provision of a washing machine which washes, rinses and dries articles placed therein and delivers them to a convenient point for unloading.

Another object of the invention is the provision of a washing machine in which the articles are fully accessible to the washing, rinsing and drying means, and are subjected to the direct spray of the wash and rinse liquids, eliminating the necessary stacking of the articles as employed by present washers.

Another object of the invention is the provision of a washing, rinsing and drying machine which can be loaded and unloaded thru the same opening simultaneously and which opening is conveniently located at the top and provided with lids which, when closed, form a work surface while the machine is either running or idle.

Another object of the invention is the provision of a washing, rinsing and drying machine which is continuous in operation and in which the article containers are halted and travel at a slower rate of speed thru the loading and unloading zones than thru the washing, rinsing and drying zones.

Another object of the invention is the provision of a washing, rinsing and drying machine which has the article conveying means completely enclosed.

A further object is to provide a washing machine with means for filtering the liquid to be recirculated by the washing and rinsing systems.

Other objects and advantages of the invention will be apparent from the following description, the accompanying drawings and the appended claims.

Referring to the drawings, which illustrate a preferred embodiment of the invention:

Fig. 1 is a cross sectional front view of the invention taken on line 1—1 of Fig. 2 with the portion 62 of the panel 38 removed.

Fig. 2 is a cross sectional side view taken on line 2—2 of Fig. 1.

Fig. 3 is a partial cross sectional front view taken with parts removed to show operation and control of float valve and drain valve and position of drying fan.

Fig. 4 is a cross sectional plan view taken on line 4—4 of Fig. 1.

Fig. 5 is a cross sectional view taken on line 5—5 of Figs. 3 and 4.

Fig. 6 is a perspective view of the article container or retainer showing connecting link chain between the container or retainer and chain.

Fig. 7 is a cross sectional view taken on line 7—7 of Fig. 1.

Fig. 8 is a cross sectional view taken thru 8—8 of Fig. 3.

Fig. 9 is a partial cross sectional view taken on line 9—9 of Fig. 1 of pump.

The drawings illustrate a washing machine which is adapted to receive articles to be washed, rinsed and dried and is provided with means for conveyance of the articles thru the wash, rinse and drying zones in continuous operation for an indefinite period of time.

The articles to be washed may be loaded thru the opening provided and unloaded thru the same opening after passing thru the washing, rinsing and drying zones. If they are not thoroughly cleansed after passing thru one cycle, they may be left to complete a second cycle. It is possible to cleanse large quantities of articles because of the flexible nature of the invention.

Inner tank

30 As shown, the washing machine consists of an inner tank 10 and an outer cabinet or cover panel 11 which rest upon a rectangular base structure 12. The inner tank comprises two end panels 13 and 14 and two side panels 15 and 16 which are secured together at their edges to form a water tight tank. The bottom 17 of the inner tank is secured to the four lower edges of the end panels 13 and 14 and the side panels 15 and 16 in such manner as to provide water tight joints. 40 The bottom panel 17 is formed upward at 18 and 19 and then angularly upward and joined at the center 20.

The bottom panel 17 is provided with offsets at 21 and 22 so that it will rest squarely upon the flanges 23 and 24 of the outer cabinet 11 and the flanges 25 and 26 of the base 12. The vertical surfaces 18 and 19 and the top surface 20 of the bottom panel 17 form a partition between the washing liquid tank 27 and the rinsing liquid tank 28 and also provide space in which is mounted the motor 29 and pumps 30.

The top edge of the inner tank 10 is flanged inwardly at 31 and upwardly at 32 to provide for a sealing element 33. The inward flange 31 and upward flange 32 and the sealing element 33 con-

tinue completely around the top of the inner tank.

A baffle 200 extends from front to back and is supported by rivets 201 on the panels 15 and 16. Slots in the downwardly turned flanges provide easy means for removing the baffle for access when cleaning. This baffle serves to prevent liquids from being sprayed thru the loading space.

Outer cabinet

The outer cabinet or cover panel is comprised of two end panels 34 and 35 and two side panels 36 and 37. The end panels are flanged horizontally inward at 23 and 24 and rest upon the flanges 25 and 26 of the base 12. The side panels 36 and 37 are likewise formed at right angles providing flanges 38 and 39 which rest upon the flanges 40 and 41 of the base 12. The top edges of the end panels 34 and 35 are formed inwardly at 42 and 43 thence upwardly at 44 and 45 and then horizontally inward, forming a portion of the top of the cabinet 46 and 47. The surfaces 46 and 47 of the outer cabinet 11 are formed vertically downward providing flanges 48 and 49 to which the hinges 50 and 51 are secured.

The side panels 36 and 37 are formed horizontally inward at 60 and 61 and then downward at 62 and 63. The surfaces 62 and 63 are formed outwardly at 64 and 65 and extend completely across the front and back sides of the cabinet as shown in Fig. 1. These flanges 64 and 65 serve as a guiding means for the article container brackets 66 and prevent any swinging motion of containers 67 when the articles are being loaded into or unloaded from the said containers.

The doors 52 and 53 are secured to the hinges 50 and 51 thru the flanges 54 and 55 by riveting or welding or any suitable means and complete the work surface or top of the outer cabinet, when in closed position, as indicated by the solid lines. The doors 52 and 53 are also flanged vertically downward at 56 and 57 to give strength and appearance to the construction. When loading or unloading the articles, the doors 52 and 53 are thrown open as shown by the dotted line positions 58 and 59. The doors in this position serve as a resting place for the articles accumulated when loading and unloading.

The top portions 46 and 47 of the end panels 34 and 35 are formed downwardly at 68, overlapping the vertical flange 69 of the side panels 36 and 37, as shown in Fig. 8. The front panel 36 and back panel 37 are provided with openings or louvres 64 and 65 thru which air is circulated for drying the articles as they pass by, carried by the article containers. Any suitable insulating material 66 is secured to the inner surfaces of the outer cabinet panels 34, 35, 36 and 37 by means of cement and serves to prevent escape of heat and noise. The front panel 36 is provided with two rectangular openings 136 and 137 thru which the drain screens are entered.

Conveyer system

The article conveyer system is comprised of a multiplicity of wire containers or baskets 67 suspended by means of brackets 68 at each side which are carried by rollers 70 and pins 71. The rollers travel in the U shaped channel elements 72 and 73 and along the top guides 74 and 75. The links 76 are pivotally connected to the brackets 68 by the pins 71. The opposite ends of the links 76 are pivotally connected to the two chains 78 and 79 which also travel in the U shaped channel elements 72 and 73 at the front and rear

of the cabinet. The two chains 78 and 79 are precisely the same length and the links 76 are secured to the chain by the rivets 77 at predetermined distances and oppositely disposed, providing the proper spacing for efficient operation and utilization of the space.

The chains are retained by the sprockets 81, 82 and 83 which are in pairs and oppositely disposed on the front and rear sides of the cabinet. The sprockets 81 and 83 are arranged in a zig-zag position across the top, causing the chains 78 and 79 to follow a zig-zag path while the containers follow a substantially horizontal path defined and supported by the guides 74 and 75. The links 76 continually drive the containers but due to the divided paths the containers move at a varying rate of speed across the top and are entirely interrupted at some points thereof. The sprockets 81 are mounted on studs 87 and the sprockets 83 are mounted on studs 88 which are rigidly secured to the front panel 16 and the rear panel 15 of the inner tank 10 in such a manner as to permit free rotation when the chain is motivated by the driver sprockets 82. The driver sprockets 82 are secured to the inner ends of the shafts 89 by set screws. The shafts 89 extend thru suitable bearings which are secured to the inner panels 15 and 16. The sprockets 90 are secured to the ends of the shafts 89 by means of set screws and lie between the outer panels 36 and 37 and the inner panels 15 and 16. Two drive chains 92 connect the sprockets 90 to the sprockets 93 which are secured to the ends of the countershaft 94 by means of set screws. The drive sprockets 93 being secured at each end to the countershaft will cause the two chains 92 to travel in unison, carrying the containers with ends oppositely disposed and hingeably secured to the links and chain, thereby permitting the baskets to always remain upright when traversing the substantially rectangular path defined by the channels on the sides and bottom and the top guides 74 and 75 at the top. The countershaft 94, Fig. 4, is driven by the gears 95, 96, 97, 98, 99 and 100. The gear 95 is secured to the shaft 94 with a set screw 101 and meshes with the gear 96. Gears 96 and 97 are rigidly secured together and are free to rotate on the motor shaft 102. The gear 97 meshes with the gear 98 on the countershaft. Gears 98 and 99 are rigidly secured together and are free to rotate on the countershaft 94. Gear 99 meshes with gear 100 which is secured to the motor shaft 102 and transmits the motor power thru the series of gears and reducing the speed of rotation to that desired for the conveyer assembly. The motor 29 has extending shafts at both ends shown at 102 and 103. The drive gears are assembled to the one end and the pump 30 to the other end.

The conveyer chains pass over a pair of lower sprockets 83 and over the tops of a pair of upper sprockets 83 for producing an interrupted movement of the containers. As the links, pivoted to the chains and containers, move along the straight line from the lower to the upper sprockets 83 the forward movement of the containers is interrupted and the containers will move backwardly a slight amount as the link continues its upward movement over the upper sprockets 83. The containers in this manner are retained in substantially stationary position for a period of time near the opening provided in the top of the cabinet. It will be further noted that the containers are retained in vertical position at all times as they are moved

along the sides of the cabinet, over the spray nozzles and across the loading and unloading opening in the top of the cabinet.

It is to be understood that the word "container," wherever used, is to mean any device or means suitable for holding the articles to be washed.

Transmission and pump

The motor 29 is preferably mounted on a suitable support 104 which rests on the inturned flanges 38 and 39 of the side panels. The motor may be any suitable means for supplying power, but preferably the ordinary electrical motor will be considered as the above means described. The motor is provided with a base 105 and is secured to the support 104 with bolts 106. Wires 190 and 191 are provided and adapted to connect to suitable electrical sockets and controlled by a switch 192 located on the front of the cabinet.

The pump assembly 30 is of dual construction and consists of three castings forming the housing, and two impellers which are secured on the extended motor shaft by means of set screws. The inner housing 107 is recessed to receive the impeller 108 and is provided with an inlet 109 and an outlet 110. The inlet is secured to the wash solution tank 27 and is mated with an aperture therein to provide ingress of the solution from the tank to the pump. The outlet is connected to the tube 111 which conveys the liquid to the spray system. The housing is further provided with a recess at the end toward the motor. This recess is concentric with and encompasses the shaft, providing suitable space for a sealing element 112. The sealing element is pressed into close relation to the motor shaft by the nut 113 and may be adjusted to prevent leakage of the pump liquid around the shaft. The center partition 114 of the pump forms the outer wall of the wash liquid pump and the inner wall of the rinse liquid pump. The outer housing 115 in combination with the center portion 114 forms the complete housing for the rinse liquid pump. Suitable gaskets 116 are placed between the outer and inner housings and the center portion of the pump to insure against leakage of the pump housing. The outer housing 115 is provided with an inlet 117 and an outlet 118. The inlet is secured to the rinse solution tank 28 and is mated with an aperture therein to provide ingress of the solution from the tank to the pump. The outlet 118 is connected to a tube 119 which conveys the liquid to the spray system. The inner housing is further provided with a support base 120 which is secured to the support 104 by any suitable means, but preferably bolts 121. Although a preferred design of pump is herein described, it is to be understood that any suitable dual pump or combination of separate pumps may be used.

Spray system

The spray system consists of two series of pipes and spray nozzles, one furnishing wash solution from the tank 27 and the other furnishing a rinse liquid from the rinse tank 28. The tube 111 conveying the wash solution extends horizontally at 122, Fig. 4, to the rear of the machine and then upwardly at 123, thence diagonally at 124, Fig. 1, and thence horizontally at 125 and 126 toward the front. Spray nozzles 127 are connected at predetermined distances to the tubes 125 and 126 and directed to spray on the articles as they are carried by in the containers. A tube 128, Fig. 1, is connected to the tube 111 and extends angularly across the back and thence horizontally forward at 129 and 130. Spray nozzles 127 are connected

at predetermined distances to the tubes 129 and 130 and directed to spray at diagonally opposed angles and causing wash solution to be sprayed at the under side of the articles as they pass in the conveyer containers.

Tube 119, Fig. 4, which conveys the rinse liquid is likewise extended horizontally toward the rear, thence upwardly at 131, horizontally across the back at 132, thence horizontally forward at 133 with extending nozzles 194 directed angularly downward. A pipe 134, Fig. 1, is connected to the pipe 119 and extends horizontally to the left at the back, thence horizontally forward at 135 and also is provided with nozzles 194 directed angularly upward. The tubes 135 and 133 and connecting tubes and nozzles constitute the rinse spray system supplying a rinse spray from the tank 28 thru means of the rinse side of the pump 30.

It will be noted that the liquid from both the wash and rinse nozzles will be sprayed against the utensils and fall upon the drain panel 140, and directed thru the openings 141 and 142, then thru the filters and drain screens 143 and 144 and back into the tanks 27 and 28 respectively, where it is again circulated thru the pump and spray system. The opposed angles of the drain panel 140 cause the wash and rinse liquids to return to the wash and rinse tanks respectively. The drain panel is supported by means of rivets 149. The flanges 150 are slotted to enable the removal by merely lifting the drain panel upward.

Drain screen

The drain screens 143 and 144 are secured to the bottom of rectangular flanged, drawer shaped containers 145 and 146. Filters 147 and 148 are placed upon the screen in the bottom of the drain screen assembly and serve as a sanitary and desirable means of disposing of refuse filtered from the wash and rinse liquid. When the utensils have been washed, rinsed and dried, the filters are taken from the drain screens and disposed of and replaced by new ones. Paper filters which are inexpensive are preferred, but it is to be understood that fabric or other materials may be used without departing from the scope of the invention. If fabric or other suitable filters are used they can be removed, cleansed and replaced. The drain screen assemblies are removed thru the openings 136 and 137 of the front panel 36 for cleaning. Suitable handles 149 and 150 are secured to the front of the drain screen retainers for the purpose of removal. Guides 151 and 152 are secured to the drain panel 140 for supporting the drain screen assemblies.

Liquid control

The inlet valve 153 is secured to the back wall 15 of the inner tank 10 thru an aperture 154 and is held in place by means of a nut 155. A gasket 156 serves to prevent leakage around the aperture 154. A pipe 157, preferably connected to the hot water system, is fitted into the valve at 158 and supplies water to the tank 28. It is apparent that when the tank is empty the float 159 will drop and open the orifice 160 and permit water to enter the tank due to the pressure of the water system. A stud 161 is secured to the top of the float and extends thru an aperture in the control rod 162. A collar 163 is secured to the top of the stud 161 at spaced relationship to the float, permitting a predetermined movement of the float relative to the control rod 162. A lever 164 is rigidly secured to the float stud 161 and pivotally connected to a lug 165 of the valve 153 by means of a

pin 166. A screw 167 is threaded into a projecting lug 168 of the lever 164 and engages the valve stem 169. The valve stem is provided with a sealing element 170 which prevents passage of the liquid when the float is in raised position as shown in Fig. 5. A spring 171 is positioned to urge the valve stem to open position when the float drops below the water level line.

Referring to Fig. 3 an arm 172 is connected to the control rod 162 by insertion thru a hole in the end of said arm and is held in position by pins 173. The other end of the arm is pivotally secured to the wall of the inner tank by means of a rivet 174. Intermediate of the ends of the arm, the drain valve stem 175 is pivotally connected by means of the pin 176. A sealing means 177 is rigidly connected to the lower end of the valve stem and is positioned to seat in a correspondingly shaped aperture, to prevent egress of the liquid thru the drain valve when the sealing means 177 is in its lowered position as shown in Fig. 3. The sealing means 177 is acted upon by the spring 178 tending to force said sealing means to closed position. The valve housing 179 is constructed with an inlet 180 which is connected to the wash tank by means of a pipe 181 and a second inlet 182 which is connected to the rinse tank by means of a pipe 183. The opening 188 is provided and is preferably connected to any convenient drain system and carries the liquid from both the wash and rinse tanks to said drain system. A heating element 186 is provided to increase or maintain temperature of the rinse liquid. The control rod 162 is extended upward along the inner wall of the tank and is connected to a control handle 184 by means of an arm 185 and stud 186 which extend thru to the outside of the cabinet. A tube 187 extends thru the vertical walls 18 and 19 of the inner tank. A valve 188 of the type which permits the liquid to flow only in one direction—namely, from the rinse to the wash tanks is connected to the end of the tube 187 at the wash liquid side.

Drying system

A fan 188, Figs. 2 and 3, is positioned directly behind the louvres 84 of the front panel and is driven by means of an electric motor or any other suitable means and serves to circulate relatively dry air from outside the cabinet thru the louvres 84 and across the articles as they pass in the containers, thereby removing the droplets of liquid and causing the articles to be dried. Louvres 85 are provided in the back panel directly opposite to the louvres 84 and provide means for the air to escape. A heating coil 189 may be placed between the fan and the articles to be dried, causing warm air to be circulated across the articles, facilitating a speedy drying action. The coil 189 is connected to a suitable current supply by means of the wires 187 and 188.

Operation

To operate the machine, the control handle 184—A is shifted from the position as shown in dotted lines Fig. 3 to position as shown by solid lines (184) which causes the control rod 162 to drop. The float 189 is thereby released allowing the liquid to enter the valve 168 which is thereby opened. The liquid flows thru the port 160 and the valve outlet 188 into the rinse tank 28. The release of the control rod 162 also operates the arm 172 and the valve 178 to close the drain openings in both the wash and rinse tanks. When the liquid has risen to the level of the tube 187 it flows thru said tube until the wash tank 27 is filled and the liquid in the rinse tank rises to a point slightly

higher, raising the float and closing the inlet valve. The control switch 192 is then turned on causing the conveyors 78 and 79 and the containers 67 to travel the predetermined path within the cabinet and the pumps to circulate the liquid from both tanks thru the spray system. The articles to be washed are placed in the two containers at the top of the machine, Fig. 1, and in each successive container as it passes the opening at the top of the cabinet. The containers pass to the right and then down the right side of the machine where a wash liquid (such as soap and water) is sprayed upon the articles from different angles by the spray nozzles 127, which are located to the right of the center line of the machine. The wash liquid drains from the articles back into the wash tank 27 and continues to recirculate thru the wash liquid system. The articles continue across the bottom of the machine, passing to the left and upward where they receive a spray rinse from the nozzles 194. As they pass the fan 189, Fig. 3, the water is blown from the articles causing them to dry. The heat from the hot liquid which is ordinarily used also facilitates the drying. When the containers reach the opening at the top the articles are removed and other articles are replaced for continued washing. It is apparent that continuous washing for an indefinite time is possible merely by removing the cleansed articles from the containers and placing others to be washed while the containers are stationary at or are slowly passing the opening at the top of the machine. To further facilitate the loading and unloading of the machine the novel arrangement of chains and links causes the containers to move at a slower rate of speed while passing the opening at the top at certain points in which the movement is interrupted. When the articles have been washed the control handle 184 is shifted to the position 184—A as indicated by the dotted lines, causing the control rod to hold the float in closed position, and opening the drain valve 178, to empty the tanks. The control switch is then operated to stop the motor.

What is claimed is:

1. In a washing machine; a conveyer, means for driving said conveyer, means for guiding said conveyer in a predetermined path, means for guiding said conveyer in a zig-zag path, a plurality of containers, means connecting said containers to said conveyer to follow said predetermined path while maintained in a vertical position, and means for guiding said containers in a horizontal path while being maintained in a vertical position as said conveyer is guided in said zig-zag path while slowly advancing said containers.

2. In a washing machine; a conveyer, means for driving said conveyer, means for guiding said conveyer in a predetermined path, means for guiding said conveyer in a zig-zag path, a plurality of containers, means connecting said containers to said conveyer to follow said predetermined path, and means for guiding said containers in a different path than said conveyer as said conveyer is guided in said zig-zag path while slowly advancing said conveyers, and means for retaining said containers against swinging movement when moving in said different path.

3. In a dish washing machine, a central baffle, washing and rinsing nozzles disposed beneath said baffle, a series of containers, supporting means for said containers to which the containers are permanently attached, means for driving said supporting means, means for guiding the con-

ainers in a U-shaped path along the sides and across the bottom of the machine, and means arresting the advancement of the containers at the top of the machine while the supporting means continues to advance.

4. In a dish washing machine, a central baffle, washing and rinsing nozzles disposed beneath said baffle, a series of containers, supporting means for said containers to which the containers are permanently attached, means including a motor for driving said supporting means, means for guiding the containers in a U-shaped path along the sides and across the bottom of the machine, and means reducing the speed of the advancement of the containers at the top of the machine while the supporting means continues to advance, a central compartment in the bottom of the machine containing the driving motor, said central compartment forming a reservoir at either side thereof for rinse and wash water respectively.

5. In a dish washing machine, a tank, inwardly presenting U-shaped channels at opposite sides of said tank, continuous chains disposed in said channels, means for driving said chains, links on said chains, containers permanently supported on said links, rollers on said containers operating in said channels, guide means disposed across the open ends of said channels engaged by said rollers, and means for supporting the chains in zig-zag paths adjacent to said guide means for reducing the speed of advancement of the containers in a straight line across said guide means as the chains continue to advance.

6. In a dish washing machine, a tank, a chain in said tank, supported for movement in a rectangular path on three sides of the tank and a zig-zag path along the other side thereof, containers permanently attached to said chain, means for driving said chain and containers, and means for reducing the advancement of said containers along a straight path while the chain is advancing along said zig-zag path.

7. In a conveyer system, a pair of spaced chains, means for guiding said chains in a U-shaped path, additional means for guiding said chains in a serpentine path across the end of the legs of said U-shaped path, containers on said chains mounted to be retained in a vertical position, means guiding said containers to follow the U-shaped path of said chains, and means for advancing said containers at a reduced speed along a straight path while retained in a vertical position as said chains are passing over said serpentine path at a higher speed.

8. In a dish washing machine, conveyer means, means for driving said conveyer means at a constant rate of speed, a plurality of supporting elements pivoted at spaced points on said conveyer means, means for maintaining said supporting elements in the path of travel of said conveyer means over a portion of the travel thereof, and means for interrupting the movement of said supporting elements as said conveyer means continues to move at said constant rate of speed, and washing nozzles directed over said supporting elements in that portion of the path of movement in which the supporting elements travel with the conveyer means.

9. In a conveyer system, conveying means, a plurality of baskets, links pivoted to said baskets and to said conveying means with the baskets supported in carrying position, means for directing each basket while maintained in carrying position along a predetermined straight path as it is moved there along by said conveying means, means for directing said conveying means and one end of the link along a diverging path which reduces the speed of movement of the other end of the link and the basket relative to that of the conveying means, and means for driving said conveying means at a constant speed.

10. In a conveyer system, a pair of spaced conveyer chains, a plurality of elements, links permanently pivoted to said elements and said chains for supporting said elements in carrying position, means for guiding said chains in a predetermined path over a portion of their path of movement along with said elements, means for directing said elements along a straight path, and means for simultaneously directing said chains over a serpentine path to reduce the speed of movement of the elements along said straight path.

11. In a conveyer system, conveying means, a plurality of elements, intermediate means connecting said elements to said conveying means in such manner as to permit the elements to both pivot and move independently of the conveying means as they are driven thereby, means for directing each element, while maintained against pivotal movement, along a predetermined straight path as it is moved there along by said conveying means, means for simultaneously directing said conveying means along a diverging path which reduces the speed of movement of the element relative to that of the conveying means, and means for driving said conveying means at a constant speed.

ALFRED H. HABERSTUMP.
